PAPER ROLL HOLDER

Filed Sept. 19, 1949

UNITED STATES PATENT OFFICE

2,568,877

PAPER ROLL HOLDER

Robert A. Williams, Los Angeles, Calif., assignor
to McClintock Manufacturing Company, Los
Angeles, Calif., a corporation of California

Application September 19, 1949, Serial No. 116,447

4 Claims. (Cl. 242—55.5)

1

This invention is concerned with a paper roll holder, it being a general object of the invention to provide a paper roll holder of simple, effective, improved construction and operable to carry a roll of paper in a most convenient and advantageous manner and so that paper can be used from or withdrawn and severed as required for use.

The structure of the present invention involves a frame formed of spaced vertical standards which are of box-like construction and a head which extends between and is fixed to the upper ends of the standards. The invention provides a simplified, inexpensive, sturdy standard construction and provides a dependable secure means of joining the head of the frame to the standards. A roll mounting is carried beneath the head and between the standards and involves, primarily, a rod, the ends of which are engaged in upwardly opening sockets in the standards, openings and guideways being provided for convenient passage of the rod into and out of operating position. A cutter or roll holder is provided and involves arms, one at each standard, means in the form of a hook construction pivotally coupling each arm to its supporting standard, a blade extending between the outer ends of the arms and means coupling the ends of the blade to the ends of the arms so that these parts are permanently joined for limited movement or flexibility of the blade relative to the arms. A means is provided for operating the cutter, which means involves a leaf spring in each standard having its lower end anchored through a simplified, effective construction while its upper end bears against the arm pivoted to the standard, there being an abutment intermediate the end portions of the spring over which the spring is flexed, the abutment being adjustable from the exterior of the standard.

It is a general object of this invention to provide a construction of the general character referred to which involves few simple easily formed parts which cooperate to establish a slightly sturdy practical mechanism and which are such that they can be assembled in a most convenient manner.

Another object of the invention is to provide a simplified, practical frame construction for a device of the character referred to. The frame provided by the present invention is formed entirely of light or thin sheet metal, the formation and relationship of parts being such that the frame thereof formed of light metal is rigid and sturdy and is of neat smooth appearance.

2

A further object of the invention is to provide a simplified unique construction relating the paper cutter to the frame through which construction the arms of the cutter are latched or hooked to the frame and when thus engaged with the frame are acted upon by the springs carried by the standards of the frame so that the arms are individually operated in the desired manner.

The various objects and features of my invention will be fully understood from the following detailed description of a typical preferred form and application of the invention, throughout which description reference is made to the accompanying drawings, in which:

Fig. 1 is a perspective view of the construction provided by the present invention, showing a roll of paper in place in the device. Fig. 2 is an enlarged transverse sectional view of the structure provided by the present invention taken immediately inside one standard of the construction, being a view taken substantially as indicated by line 2—2 on Fig. 1. Fig. 3 is a detailed sectional view taken as indicated by line 3—3 on Fig. 2. Fig. 4 is an enlarged, detailed sectional view taken as indicated by line 4—4 on Fig. 2. Fig. 5 is a plan section taken as indicated by line 5—5 on Fig. 2. Fig. 6 is a view taken as indicated by line 6—6 on Fig. 3 with parts broken away to show details of construction. Fig. 7 is a plan section taken as indicated by line 7—7 on Fig. 6. Fig. 8 is an enlarged detailed sectional view taken as indicated by line 8—8 on Fig. 2. Fig. 9 is a sectional view taken as indicated by line 9—9 on Fig. 8. Fig. 10 is an enlarged detailed sectional view taken as indicated by line 10—10 on Fig. 2 and Fig. 11 is a detailed sectional view taken as indicated by line 11—11 on Fig. 4.

The construction provided by this invention is intended primarily to rotatably support a roll A of paper, or the like, and is such that it can be used to advantage on a counter or other suitable stand or support, this type of device being of the character employed in stores and various industrial or commercial establishments where paper is used from a roll. The device of the present invention involves, generally, a frame formed of standards B and a head C extending between the standards. A roller mounting D is carried between the standards B beneath the head C and supports the roll A of paper and a cutter or roll holder is carried by the standards and involves arms E attached to the standards and a blade F carried by the arms. Means are carried by or provided at the standards B to operate the arms E and each involves a leaf

spring G and an adjustable abutment H engaged by the spring and governing the action thereof.

The standards B are spaced vertically disposed elements or units preferably formed of sheet metal, and since they are alike I will describe one, it being understood that such description is applicable to both.

Standard B in accordance with the present invention is characterized by a flat vertically disposed outer wall 10, inwardly projecting front and rear edge walls 11 and 12, a base 13, top 14, and an inner wall 15 spaced inwardly from the wall 10 so that a chamber 16 is established in the standard.

The outer wall 10, edge walls 11 and 12, base 13 and top 14 are preferably formed as a single or integral unit, in which case the edge walls 11 and 12 are in the nature of flange-like projections that extend inwardly from the vertical edges of the outer wall 10 while the base 11 extends horizontally and inward from the bottom edge of wall 10 and the top 14 extends horizontally from the upper edge of wall 10. In the preferred construction the upwardly extending or vertical edges of the wall 10 are not truly vertical, but converge somewhat so that the standard is upwardly convergent or tapered, as shown throughout the drawings.

The inner wall 15 is preferably a substantially flat plate-like part that depends from the edge 18 of top 14 and extends between the edges 19 of the edge walls 11 and 12.

In accordance with the present invention the inner wall 11 is rigidly fixed to or is joined with the unit which includes the outer wall 10, and in the case illustrated it has a bottom 20 that extends between its lower end and the wall 10 and adjacent the inner side of wall 10 it has a depending flange 22. Ears 23 are struck from the wall 10 as by punching, so that they are upwardly faced and are spaced inward from wall 10 so that the flange 22 is received between them and the wall 10 in the manner illustrated in Fig. 3. Near the upper end portion of the standard two horizontally spaced pins 30 and 31 extend between and connect the walls 10 and 15. In the case illustrated the pins 30 and 31 are riveted to wall 15, as at 32 and 33, respectively, while their outer ends are releasably fastened to wall 10 by suitable screw fasteners 34.

The head C is an elongate horizontally disposed element formed of sheet metal and in its preferred form it has a flat top 35 and depending sides 36. The ends of the head C are joined to the upper ends of the standards B so that the top 35 adjoins and is flush with the tops 14 of the standards while the sides 36 of the head are flush with and adjoin the edges 10 and 11 of the standards. In the form of the invention illustrated the upper ends of the standards are permanently joined to the ends of the head C and in the case illustrated the desired connection is provided by establishing a flange 37 on the upper end of wall 15 to engage under the top 35 of the head and by establishing flanges 38 on the wall 15 to engage inside the sides 36. The flanges 37 and 38 are preferably secured to the head C as by welding.

In the preferred form of the invention the frame further includes a stretcher 40 which extends between the bases of the standards. In the case illustrated each base has an upwardly projecting part 41 forming an abutment to be engaged by the spreader 40 and ears 42 are struck from the bases adjacent the abutments

41 and overlie the end portions of the spreader 40 and serve to connect the spreader to the bases with the ends of the spreader in engagement with the abutments 41. In the preferred form of the invention the spreader 40 is ribbed so that it may be light and at the same time rigid. When a ribbed construction is employed the ears 42 may be shaped to engage around the ribbed spreader construction as clearly shown in Figs. 2 and 10 of the drawings.

The roller mounting D preferably involves an elongate bar or rod adapted to be engaged through the core elements 44 of the roll A. The rod is of such length that its ends project somewhat beyond the ends of the roll A and the structure is such that the roll A fits between the standards B with suitable clearance while the ends of the rod D are engaged with or supported by the standards. In the preferred construction the front edge wall 11 of each standard is cut away to form an opening at 46 and the inner wall 15 has a guideway 47 formed in it, extending inwardly from the opening 46 and terminating at an upwardly facing notch or socket 48. The sockets 48 in the walls 15 of the two standards receive the end portions of the rod that carries the roll A so that the roll is effectively supported for rotation between the standards. In the particular case illustrated the rod 49 is a simple straight tubular element in the form of a length of pipe, or the like.

The arms E are related to the standard so that there is one arm carried by such standard. Each arm in accordance with the preferred form of the invention is an elongate sheet-metal part with a body portion 50 and an inwardly projecting marginal flange 51 which makes the arm somewhat cup-shaped or cup-like and which materially stiffens the arm.

The means provided for pivotally coupling or connecting arm E with its supporting standard B preferably utilizes pin 30 which connects walls 10 and 15 and which is spaced inward somewhat from the front edge wall 11. The arm E has a notch 53 extending into it from its upper edge and in the preferred construction the notch extends inwardly and rearwardly in the arm establishing a hook-like part 54 engageable around the pin 30 in the manner illustrated in Fig. 6 of the drawings. The notch 53 is spaced somewhat from the inner end 56 of the arm so that the arm has an inner end portion 57 that receives the pin and has an outer end portion which opens at an edge of the arm such as the foremost edge 55 of the arm. The arm projects forward through a notch or opening 60 in the front edge wall 11 of the standard. Through the construction just described the arm E can be easily inserted into the cavity or chamber 16 of the standard and there manipulated so that the part 54 hooks around the pin 30 so that the pin is received in the notch 53. In the preferred construction the pin has a reduced portion 61 on which the arm is hooked or carried so that the arm is held adjacent the wall 15 of the standard.

The blade F may vary in form and construction. However, it is preferably a simple, elongate strip that may be shaped or ribbed as shown in Fig. 2 of the drawings so that it is rigid and has parts 65 which bear on the roll A while an edge 66 is presented over which the paper can be torn or by which the paper is cut in the manner similar to structures of this general character.

In accordance with the preferred form of the

invention each end of the blade F is attached to an arm E to have limited pivotal movement and so that it can vary somewhat as to angle or pitch relative to the arm, as circumstances may require. In accordance with the present invention the connection at each end of the blade involves a tab-like extension 70 projecting from or beyond the end of the blade and entering an opening or hole 71 in the body 50 of the arm. The extension 70 is preferably an integral part of or continuation of the blade and the opening 71 is preferably a round opening or bore which receives the extension 70 so that the blade can turn about an axis concentric with the opening 71. A laterally extending part or retainer 72 is provided on the outer end of extension 70 or beyond the outer side or body 50 of the arm and is of such extent as to positively prevent displacement of the extension 70 from the opening 71. In accordance with the present invention the end portion of the blade enters between the cup-like construction of the arm and the blade engages or cooperates with the flanges 51 of the arm to limit the pivotal movement of the arm. In the case illustrated the extreme end portion 75 of the blade is proportioned or shaped to cooperate with the flanges 51 so that the blade has the desired pivotal movement. It will be observed that through the construction just described the end portions 75 of the blade are suitably housed within or concealed by the arms and the blade, in addition to being free to turn relative to the arms may rock or twist somewhat relative to the arms in the event that one arm is operated out of synchronism with the other.

The spring G carried by each standard is preferably an elongate spring element or unit and it may, as shown in the drawings, be formed of a plurality of leaves or separate parts so that it has the desired strength and at the same time has suitable flexibility. In the case illustrated the spring G is of laminated construction and it extends upwardly from a point adjacent the bottom 20 of wall 15 to a point somewhat above and between the pins 30 and 31. The lower end of the spring is anchored in the chamber 16 or to the standard. In the case illustrated an inward projection 80 is provided on wall 15 and enters a notch 81 in the edge of the spring near its lower end. The engagement of the projection in the notch 81 holds the spring down and the disposition of the spring in the structure, as will appear from the drawings, causes it to tend to bear forward at its lower end, which action of the spring is checked by a stop 82 in the form of a lug struck upwardly from the bottom 20, as shown in Figs. 4 and 11 of the drawings.

The spring abutment H engages the intermediate portion of the spring and is preferably so adjusted that the upper end portion of the spring that occurs between the pins 30 and 31 tends to move forward or toward the front edge wall 11. The arrangement and relationship of parts is such that the forwardly pressing upper end portion of the spring G engages the inner end portion 57 of the arm. In the preferred construction an anti-friction roller 85 is carried on the arm portion 57 by means of a pivot pin 86 and the spring bears on or engages the roller.

The spring abutment H is preferably in the form of a screw horizontally disposed in the chamber 16 to engage the middle portion of the spring G. The screw is guided or carried by inwardly struck lugs 87 and 88 that project from wall 15 and it may be threaded through one of

the lugs as, for instance, through lug 88. The screw 89 projects from the standard through a suitable opening 90 in the rear edge wall 12 and is provided at its outer or projecting end with a handle 91 by which it can be conveniently rotated or operated.

From the foregoing description it will be apparent that the frame with the standards B assembled with the head C and with the springs 10 G in the standards and engaged by the adjusting screws H may be constructed or assembled and may be readily shipped or handled with the arms E detached, the arms being coupled to the ends of the blade F through the construction 15 above described. When the structure is ready for use the inner end portions 57 of the arms may be inserted in the chambers 16 of the standards against the forward pressure of the springs G and when the arms have been hooked to the pins 20 30 the structure is ready for use. To insert the roll A in the structure it is preferred that the arms be swung up to a position such as is indicated in dotted lines in Fig. 2, in which case the action of the springs against the end portions 25 57 of the arms holds the arms in the up position. When the roll has been arranged in place the arms can be swung down or to a position such as is shown in full lines in Fig. 2, in which case the springs act on the inner end portions of the 30 arms to cause the long or outer end portions of the arms to bear downwardly and thus hold the blade F in the desired pressure engagement with the roll A. As the structure is operated the blade maintains desired pressure engagement with the 35 roll and as paper is used from the roll the blade will follow the roll until the paper is entirely consumed.

Having described only a typical preferred form and application of my invention, I do not wish to be limited or restricted to the specific details herein set forth, but wish to reserve to myself any variations or modifications that may appear to those skilled in the art and fall within the scope of the following claims:

Having described my invention, I claim:

1. A roll holder of the character described including, end standards, a head extending between the standards, a roll mounting rod carried between the standards, arms pivotally carried by the standards, and a blade carried by the arms and engageable with the roll; each end standard including a flat vertical outer wall extending continuously from the top to the bottom of the standard, front and rear edge walls integral with and projecting inwardly from the vertical edges of the outer wall, a horizontal base integral with and projecting inwardly from the lower end of the outer wall, a horizontal top integral with and projecting inwardly from the top end of the outer wall, a flat vertical inner wall spaced inwardly from the outer wall depending from the top wall and extending between the edge walls, and means rigidly joining the inner wall to the other parts of the standard including, horizontally spaced upwardly projecting ears on the outer wall at the inner side thereof and a depending lip at the lower end portion of the inner wall engaged behind the ears and a pin spacing and connecting the upper end portions of the inner and outer walls, the pins including a threaded part releasably holding one of the walls.

2. A roll holder of the character described including, a frame having spaced end standards each with spaced vertical inner and outer walls defining a chamber open at the front of the

holder and with a fixed horizontal pin carried by and extending between said walls, a roll supporting rod extending between and supported by the standards, arms entered in said chambers from the front of the holder and having forwardly faced notches receiving the pins whereby the arms are hooked to the pins to pivot thereon, and springs carried by the standards with forwardly bearing portions in the chambers operatively engaging the arms and yieldingly holding the arms engaged with the pins, and a blade carried by and between the forward end portions of the arms.

3. A roll holder of the character described including, a frame having spaced end standards each with an arm carrying pin, a roll supporting rod extending between the standards, arms hooked to the pins to pivot thereon, and a blade pivotally carried by and between the arms, each arm being an elongate cup-shaped sheet metal element having a flat body with spaced edge flanges and with a pin receiving notch in the body extending diagonally into it from one edge, the end portions of the blade being engaged between the flanges of the arms and cooperating therewith to limit pivotal movement of the blade, and springs carried by the standards and having forwardly bearing portions engaging the arms and yieldingly holding the arms engaged with the pins.

4. A roll holder of the character described including, spaced sheet metal roll carrying standards each including a vertical outer wall, edge walls projecting inwardly from the vertical edges of the outer wall and an inner wall spaced from

the outer wall and extending between the edge walls, one of the edge walls having an opening therethrough, a blade carrying arm pivoted between the walls of each standard, an arm operating leaf spring between the walls of each standard and having an arm engaging outer end portion, and spring adjusting means carried by each standard including, two spaced lugs integral with the outer wall of the standard and projecting inwardly therefrom and an abutment screw extending through said opening and through said lugs and having a spring engaging end portion, the screw being slidably supported by one lug and being threaded to the other lug and bearing against the spring at a point spaced from said end portion.
